COMBINED CIGARETTE LIGHTER AND PEN HOLDER

Leonard Willard Dangler, 14 E. 34th St., New York, N.Y.

Filed Nov. 24, 1959, Ser. No. 58,452

Term of patent 14 years

(Cl. D48—27)

Fig. 1 is a front perspective view of a combined cigarette lighter and pen holder showing my new design with a pen shown in broken lines for illustrative purposes only.

Fig. 2 is a perspective view thereof as seen from the opposite side of Fig. 1.

Fig. 3 is a rear elevational view thereof.

Fig. 4 is a fragmentary perspective view thereof with the lighter cover shown in open position.

The bottom of the combined cigarette lighter and pen holder is substantially plain.

I claim:

The ornamental design for a combined cigarette lighter and pen holder, substantially as shown and described.
